UNITED STATES PATENT OFFICE

2,355,417

LIQUID FUEL BURNER AND THERMAL CONTROL VALVE THEREFOR

James L. Breese, Santa Fe, N. Mex., assignor to
Oil Devices, Santa Fe, N. Mex., a limited partnership of Illinois

Application September 18, 1941, Serial No. 411,329

6 Claims. (Cl. 158—91)

My invention relates to an improvement in hydrocarbon burners and has for one purpose to provide a burner for burning liquid hydrocarbon fuels which shall be simple, economical and efficient in operation.

Another purpose is to provide improved means for supplying a burner through a single passage or inlet member with all of the air necessary to support the primary combustion of the fuel.

Another purpose is to provide improved means for regulating or cutting off the fuel supply in response to heat conditions.

Another purpose is to provide means for adjusting such regulating or cutoff feature.

Other purposes will appear from time to time in the course of the specification.

I illustrate my invention more or less diagrammatically in the accompanying drawings wherein:

Fig. 1 is a vertical axial section of the burner; 20

Fig. 2 is a similar section through a variant form of the device;

Fig. 3 is a section on the line 3—3 of Fig. 2;

Fig. 4 is a section similar to Figs. 1 and 2 through a variant form of the device;

Fig. 5 is a section similar to Fig. 4 through a further variant form; and

Fig. 6 is an enlarged section taken on the line 6—6 of Fig. 5.

Like parts are indicated by like symbols throughout the specification and drawings.

Referring to the drawings, I generally indicate a combustion chamber, herein shown in the form of a drum, having a bottom or base portion 2 and, if desired, a bottom body 3 of fire brick or the like, of any suitable material.

It will be understood that the burner may be applied to a wide variety of heaters, furnaces and the like. I illustrate it, however, in connection with a water boiler 5 having a central flue passage 6. I employ a single air and fuel inlet member having an outer portion 1, herein shown as vertical, and with an open top, or any other suitable means for admitting air. It has a horizontal portion 8, which extends inwardly through the wall of the member 1, and is herein shown as terminating in a downward elbow 10 axially aligned with the flue passage 6.

Referring specifically to the form of Fig. 1, I illustrate fuel supply means in the form of an inlet passage 11 from any suitable source of fuel not herein shown, which communicates, as at 12, with the bottom of the passage 9 and delivers a flow of liquid fuel along the bottom of the passage 9. Any suitable valve means may be em-

ployed for controlling or varying the flow of fuel. I illustrate a conventional valve 13, but it will be understood that any control means may be employed, such as float chambers familiar in this field.

It will be understood that the parts are so proportioned that all of the primary air necessary for combustion is supplied by means of the passage 1 to the portion of the passage 9 where the liquid fuel flows, the inlet passage being of substantially greater capacity than is necessary for the mere supply of the liquid fuel to be burned.

Any suitable means may be employed for delivering secondary air to the space within the drum 1. I illustrate, for example, in Fig. 2 inlet passages 14 and 15, which unite at the union or neck 16 and deliver outside air to the head 17, with its air discharge apertures 18. Thus, adequate secondary air is supplied for the mixture of primary air and vaporized liquid hydrocarbon which is discharged from the downturned end 19 of the passage 9.

Referring to Fig. 4, I illustrate a form of fuel control which includes an adjustable Invar rod 20, secured to the hot end of the passage 9, at the outer end of the downwardly turned portion 10. I may employ any suitable adjusting means, but I illustrate the rod 20 as screw threaded at its end, as at 21, to receive adjusting and locking nuts 22. The rod is shown with a generally conic valve tip 23, opposed to a valve seat 24 at the end of an inwardly extending fuel inlet 25. This fuel inlet may itself be adjustable, being screw threaded, as at 26, in relation to the fixed outer end wall 27 of the passage 9. 28 is any suitable collar surrounding and locked to the outer end of the passage 9 and supporting a stuffing box 29 for the end of the fuel supply line 30. 31 is a handle adapted for the convenient rotation of the member 25, whereby the valve may be exteriorly adjusted.

It will be understood that the tube 9 is exposed to substantial heat, and when it expands under heat, it opens oil flow by unseating the needle valve 23 from the seat 24. It will be understood, of course, that any additional oil flow control means may be employed, manual or automatic, such as the conventional float valve.

Referring to Figs. 5 and 6, I illustrate a safety device which may be applied to or employed with the form of any of the above described figures. The bucket arm 40 carries a bucket 45, aligned with the delivery end of the tube or nozzle 9. The spring 46 is effective normally to hold the

bucket arm and bucket in the full line position of Fig. 5 as long as the bucket is empty. The delivery of a predetermined quantity of liquid fuel to the bucket 45 is sufficient to overcome the tension of the spring 48 and cause the arm and bucket to fall to the dotted line position of Fig. 5.

Associated with the inner end of the arm 48 is the worm 41, rotatable in the nut 42, on the fuel pipe 38a, which is mounted in the stuffing box 28. The worm 41 terminates at its inner end in a valve element 43, herein shown as conic. It is opposed to a valve seat 44 in communication with the liquid fuel line 11a. It will be understood that the parts are so proportioned and the pitch of the worm is such that, when the bucket 45 and arm 48 are in the full line position of Fig. 5, the valve 43 is in the position in which it is shown in Fig. 6, permitting the liquid fuel to flow from the liquid fuel supply line 11a into the fixed fuel pipe 38a and thence into the member 48, which is screw threaded or otherwise adjustably mounted, as at 48, in relation to the outer end of the tube 8.

It will be realized that, whereas I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of my invention are as follows:

I provide a heating device in which a liquid fuel, such as liquid hydrocarbon, may be burned. I have illustrated my device in connection with a structure suitable for a hot water heater, but it will be understood that I may apply it to space heaters, furnaces, or the like, or any other heating means.

Basically, I employ an inlet passage of substantially greater capacity than is necessary for the mere supply of a liquid fuel to be burned. In all forms of my device I illustrate the air inlet passage 7 of substantial cross sectional area, which may receive air at its open top or end and deliver the air inwardly along the passage 8. The liquid fuel is admitted either by the junction of the liquid fuel line 11 with the bottom of the passage 8 or else through the oil inlet tube 25 and past the valve 23. As a substantial length of the passage 8 is subjected to the heat of combustion within the member 1, the area through which the mixture of primary air and liquid fuel flows is highly heated. Enough air is admitted to constitute the entire primary supply of air, and the liquid hydrocarbon, in the presence of this primary air, is vaporized and forms, with the primary air, a hydroxylated mixture.

The mixture is supplied at a speed exceeding that of flame propagation, so that the mixture cannot burn back into the passage 8, with a consequent deposit of carbon. It will be understood that I may employ any means for maintaining this relatively high flow of mixture. If in any particular situation natural draft is not sufficient, I may employ a motor-driven fan, or other suitable means not herein shown.

Fuel is supplied in sufficient volume to maintain a fire which will subject the passage member 8 to a temperature sufficient to vaporize the liquid fuel and to superheat the final mixture. When the mixture escapes from the downturned end 10 of the passage 8, it receives sufficient secondary air in the space defined by the drum 1 to produce

a final mixture which is burned in the combustion chamber.

I may employ any suitable means for supplying this secondary air. I illustrate for example in Fig. 2 air passages, one or more of which may be employed for delivering air from outside the burner to the head 17, whence it is delivered, for example, through the apertures 18 to the space within the drum 1. I find it advantageous to employ such a head and to so deliver the secondary air as to maintain a zone of combustion directly adjacent the passage 8, 18, so that the liquid fuel is properly vaporized and the primary mixture superheated.

I may employ any suitable means for controlling the rate of fuel flow inwardly along the lines 11 or 38. As float chambers and the like are well known in the art, I am not indicating any particular means in the drawings.

I find it advantageous to provide means for cutting off the supply of fuel, which means is effective both when the flame is extinguished and when for any reason too much liquid fuel passes the valve 23, which last condition may arise from adjustment or mal-adjustment of the various valves.

In other words, two valve means are provided, one of which is directly controlled by the bucket 45 and its controlling lever 48, and the other by the Invar rod 28 and its cooperation with the passage member 8.

As illustrated in Fig. 4, I provide an Invar rod 28 and a valve member 23 which is opposed to a valve seat 24 on the oil inlet 25, the Invar rod being adjustably mounted on the passage member 8. When the burner is cool, no oil can pass by the valve 23. In other words, to start the burner oil would have to be bypassed around the valve 23 in sufficient quantity partially to fill the bucket 45, which would then shut off the supply through the stem 41. As soon as the liquid fuel in the cup 45 has burned away, the cup will raise and open the valve 41. In the meantime, however, the tube 8, having expanded, will open the valve 23 so that the burner will go into operation.

The function of the Invar rod 28 is to close the valve member 23 when either the fuel supply is cut off or the temperature for any reason drops below a predetermined point.

If the adjustment of the various valves is such that too much liquid fuel passes the valve member 23, it will then drop down into the bucket 45 and shut off any further supply until the liquid fuel in the bucket has been burned.

If the flame is extinguished, both safety devices come into play. By the contraction of the tube 8, the valve 23 is closed. But should this not close fast enough and a certain amount of liquid enters the cup or bucket 45, then the bucket 45 drops to the dotted line position of Fig. 5 and closes the master valve 41.

I claim:

1. In combination, in a liquid fuel burner, a burner chamber, and flue means therefor, an air inlet pipe extending generally horizontally a substantial distance into the chamber at a level intermediate the top and bottom of the chamber and terminating in a discharge end, said air inlet pipe having an exterior air inlet portion adapted to admit outside air for movement through the pipe and into the burner chamber, a liquid fuel pipe, of substantially smaller diameter than the air inlet pipe, in communication with the interior of the air inlet pipe, at a point substantially

spaced from the discharge end of the air inlet pipe, and means for controlling the flow of liquid fuel through said fuel pipe and into the air inlet pipe, the bottom of the air inlet pipe being generally horizontal, the liquid fuel being in contact with the bottom of said air inlet pipe, and the air inlet pipe being directly subjected to the heat of combustion taking place within the burner chamber.

2. In combination, in a liquid fuel burner, a burner chamber, and flue means therefor, an air inlet pipe extending generally horizontally a substantial distance into the chamber at a level intermediate the top and bottom of the chamber and terminating in a discharge end, said air inlet pipe having an exterior air inlet portion adapted to admit outside air for movement through the pipe and into the burner chamber, a liquid fuel pipe, of substantially smaller diameter than the air inlet pipe, in communication with the interior of the air inlet pipe, at a point substantially spaced from the discharge end of the air inlet pipe, and means for controlling the flow of liquid fuel through said fuel pipe and into the air inlet pipe, including a fixed valve element, and an Invar rod secured to the air inlet pipe and having a valve portion opposed to said fixed valve element, the bottom of the air inlet pipe being generally horizontal to cause a relatively slow flow of the liquid fuel therealong, in contact with the bottom of said air inlet pipe, and the air inlet pipe being directly subjected to the heat of combustion taking place within the burner chamber.

3. In combination, a combustion chamber and flue means therefor, an air inlet passage element extending a substantial distance into the combustion chamber, and subjected directly to the heat of combustion in the combustion chamber, an outside connection for said air passage, a liquid fuel pipe of substantially smaller diameter than the air inlet passage in communication with the interior of the air inlet passage, a normally fixed valve element for the pipe and an Invar rod normally fixed in relation to the air inlet passage element and having a valve member at one end thereof adapted to be opposed to said normally fixed valve element, the length of the air inlet passage element between said fixed valve element and the inner end of the passage, along which the fuel which passes said valve flows, being sufficient in relation to the cross sectional area of the passage element to permit the vaporization of said liquid fuel in the interior of said air inlet passage, in response to the heat to which the passage is subjected.

4. In combination, a combustion chamber and flue means therefor, an air inlet passage element extending a substantial distance into the combustion chamber, and subjected directly to the heat of combustion in the combustion chamber, an outside connection for said air passage, a liquid fuel pipe of substantially smaller diameter than the air inlet passage in communication with the interior of the air inlet passage, a normally fixed valve element for the pipe and an Invar rod normally fixed in relation to the air inlet passage element and having a valve member at one end

thereof adapted to be opposed to said normally fixed valve element, the length of the air inlet passage element between said fixed valve element and the inner end of the passage, along which the fuel which passes said valve flows, being sufficient in relation to the cross sectional area of the passage element to permit the vaporization of said liquid fuel in the interior of said air inlet passage, in response to the heat to which the passage is subjected, and means for adjusting said normally fixed valve element toward and away from said valve member.

5. In combination, a combustion chamber and flue means therefor, an air inlet passage element extending a substantial distance into the combustion chamber, and subjected directly to the heat of combustion in the combustion chamber, an outside connection for said air passage, a liquid fuel pipe of substantially smaller diameter than the air inlet passage in communication with the interior of the air inlet passage, a normally fixed valve element for the pipe and an Invar rod normally fixed in relation to the air inlet passage element and having a valve member at one end thereof adapted to be opposed to said normally fixed valve element, the length of the air inlet passage element between said fixed valve element and the inner end of the passage, along which the fuel which passes said valve flows, being sufficient in relation to the cross sectional area of the passage element to permit the vaporization of said liquid fuel in the interior of said air inlet passage, in response to the heat to which the passage is subjected, and additional means for cutting off or reducing the fuel flow upon the delivery to the burner of an excess of liquid fuel.

6. In combination, a combustion chamber and flue means therefor, an air inlet passage element extending a substantial distance into the combustion chamber, and subjected directly to the heat of combustion in the combustion chamber, an outside connection for said air passage, a liquid fuel pipe of substantially smaller diameter than the air inlet passage in communication with the interior of the air inlet passage, a normally fixed valve element for the pipe and an Invar rod normally fixed in relation to the air inlet passage element and having a valve member at one end thereof adapted to be opposed to said normally fixed valve element, the length of the air inlet passage element between said fixed valve element and the inner end of the passage, along which the fuel which passes said valve flows, being sufficient in relation to the cross sectional area of the passage element to permit the vaporization of said liquid fuel in the interior of said air inlet passage, in response to the heat to which the passage is subjected, and additional means for cutting off or reducing the fuel flow upon the delivery to the burner of an excess of liquid fuel, including bucket means adapted to receive excess liquid fuel, said bucket means being adjacent and beneath the discharge end of the air inlet passage element, and a valve in said liquid fuel pipe, and an actuating connection between said valve and said bucket means.

JAMES L. BREESE.
